DESUPERHEATER

John Edwin Wood, Eltham, England, assignor to
The Superheater Company, New York, N. Y.

Application April 4, 1935, Serial No. 14,553
In Great Britain April 19, 1934

4 Claims. (Cl. 122—479)

This invention relates to improved means for regulating the temperature at which steam will be delivered from a steam superheater incorporated in a boiler. Generally a convection type superheater incorporated in a boiler has a characteristic which causes the steam temperature to increase as the load increases, i. e. as the quantity of steam passing through the superheater increases and the steam temperature normally reaches a maximum at the maximum load. Certain factors other than the load cause some variations in the final steam temperature, but these variations as compared with those due to changes in load are relatively small. There are distinct thermal economic advantages to be gained by maintaining superheat constantly as high as possible over a wide range of loads up to the maximum. The maximum steam temperature which can be used safely is governed by the materials used in, and the mechanical construction of, the turbine. Any reduction of steam temperature below the predetermined safe maximum involves a loss of thermal efficiency. Due to the characteristic rise of steam temperature with increase in load in a convection superheater it is not possible to operate at the permissible maximum temperature at, say, half load, without risk of damage to the turbines at higher loads unless compensating means are employed to maintain superheat at the required figure at all loads higher than half load and thus prevent increases of temperature.

Various means have been proposed heretofore for regulating the temperature of steam delivered by convection type steam superheaters which involve the use of a desuperheater arranged between the initial and final portions of the superheater.

It is the principal object of the present invention to provide a simple and efficient means for controlling the ultimate temperature of steam delivered by an installation comprising a convection type superheater incorporated in a boiler, the means being such as to effect automatically the required regulation of the temperature of the steam leaving the installation and maintain such temperature constant or approximately constant regardless of the load on the boiler, without necessarily employing thermostatically operated, manually-operable, float-controlled, or other valves, or of any other moving parts.

It is an object of the present invention to provide in addition to the apparatus for compensating for variations in steam temperature due to changes in load on the boiler, means whereby the

regulation of the desuperheating effected will be obtained in a manner which will compensate for the variations in superheat temperature referred to as arising from causes other than variations in the load on the boiler. 5

It is another object of the present invention to provide a steam temperature control apparatus such that the size of the desuperheater apparatus required may be reduced to the smallest practical limits, a further object being to provide 10 means to ensure circulation of the water in the desuperheater so as to prevent a rise in the concentration of solids in such water and the consequent increase in the liability of incrustation on the tubes of the desuperheater apparatus. 15

It is well known that the pressure drop in a steam superheater is a function of the load on the boiler and the present invention takes advantage of this fact.

The means for regulating steam temperature 20 according to this invention may be employed to regulate the temperature of steam after it is delivered by the superheater, or to control its final temperature by regulating the temperature of the steam after leaving the primary section 25 of the superheater and before entering the final section thereof. The desuperheater employed is of the type comprising a casing containing tubes open at their upper ends and having the water in the desuperheater, the level of which water is 30 variable to vary the desuperheating effect, subject on its surface to the pressure obtaining at the outlet of the superheater, or of the primary section of the superheater. The improved apparatus for effecting steam temperature regulation according to the invention is defined in the appended claims and will be described herein- 35 after with reference to the accompanying drawing, in which

Fig. 1 illustrates diagrammatically steam temperature regulating means, according to one embodiment of the invention, applied to regulate the temperature at which steam from the primary section of a convection type superheater, incorporated in a boiler, is delivered to the secondary or final section of the superheater, and 45

Figs. 2 and 3 illustrate diagrammatically other embodiments of the invention.

Referring to the drawing, while the invention is not restricted to superheaters incorporated in 50 any particular type of boiler it may be assumed for the purpose of this specification that the superheater installation is incorporated in a water tube boiler of the vertically inclined type; the desuperheater 1 would be disposed above the wa- 55

ter level in the upper drums and fed with water through a connecting pipe 2 from one of such drums, preferably that one into which the fresh feed water is fed and which is marked 3. As already stated, the desuperheater 1 is of the type in which the tubes 4 are open at their upper ends to the steam space above the water in the desuperheater, which water has its upper surface exposed to the incoming steam to be desuperheated. In the embodiment of the invention shown the outlet header 5 of the primary superheater 6 is connected to the top of the desuperheater 1 by a pipe 7 and the desuperheated steam is led from the bottom of the desuperheater by a pipe 8 to the inlet header 9 of the secondary section 10 of the superheater. It will be understood that the steam generated in the desuperheater mixes with incoming superheated steam from pipe 7 and passes therewith through the tubes 4.

Where the resistance to flow of the water through the connecting pipe 2 between the boiler and desuperheater is very small the level of the water in the desuperheater above that in the boiler drum 3 will depend on the pressure drop across the superheater 6. As the said pressure drop will vary approximately with the square of the load on the boiler, there will be a corresponding change in the water level in the desuperheater and a consequent alteration in desuperheating effect and in the rate of evaporation in the desuperheater due to changes in the amount of water immersed heat exchange surface.

Thus the height of the bottom of the desuperheater above the level of the water in the boiler drum 3 will determine the boiler load at which reduction in steam temperature by desuperheating commences, after which the amount of reduction in steam temperature will increase as the load increases, which is the operation required to correct the rising characteristic of a convection superheater.

If the water space of the desuperheater 1 be connected freely to the water space of the boiler drum 3 a small variation in the pressure drop across the primary superheater 6 will cause a relatively large variation in the water level in the desuperheater, and to reduce the extent of such variation in water level in the desuperheater and thereby enable the height of the desuperheater to be reduced to more convenient dimensions, a fixed resistance or choke 11 is inserted in the pipe 2 feeding water from the boiler drum 3 to the desuperheater.

The fall in pressure across this resistance 11 will be proportional to the square of the rate of water evaporation in the desuperheater, and will be added to the head of water in the desuperheater and water feed pipe 2 to balance the difference in pressure between the boiler and the desuperheater.

Boilers apparently identical in construction and similarly fired are frequently found in practice to have different characteristics, and the characteristic of any particular boiler must be brought into consideration in determining the value of the resistance or choke 11 to be placed in the water feed pipe 2 to the desuperheater. Consequently it is desirable that the construction and arrangement shall be such that should it be found on test that the predetermined resistance included in the water feed pipe 2 to the desuperheater requires to be modified, the necessary adjustment can be made without difficulty. For

example, at an appropriate position in its length the said pipe 2 may be divided and between opposing flanges on the respective pipe sections, there may be clamped a disc, block, or other member having through it an aperture or passage of the desired cross-sectional area for the flow of water, whereby adjustment of the resistance may be effected by removing the disc or equivalent and substituting therefor one having an aperture or passage of a different cross area.

In order to minimize the concentration of solids in the desuperheater water, the water feed pipe 2 to the desuperheater is shown as being supplied with water from the feed water trough 12 in the boiler drum 3 so that the water in the desuperheater will be almost pure feed water. The desuperheater may be blown down at the usual times according to boilerhouse routine, or otherwise emptied of water when necessary, in order that the water containing the concentration of solids will be discharged and replaced by fresh water from the feed trough.

While the temperature regulating means according to the embodiment of the invention shown in Fig. 1 will be effective to maintain constant or approximately constant the final steam temperature notwithstanding variations in the load on the boiler, those variations in temperature which are due to changing fire, feed water and other conditions may not be wholly compensated, but fluctuations in steam temperature at any given load will be damped owing to the variations in heat transfer in the desuperheater which will accompany these fluctuations.

Reference will now be made to Fig. 2 of the drawing, in which are shown certain modifications of the apparatus shown in Fig. 1; the parts which are identical with those shown in Fig. 1 are given the same reference numbers as in that figure and will not be further described.

According to the embodiment of the invention illustrated by Fig. 2, means are provided for adjusting the pressure drop between the steam space of the boiler and the steam inlet to the desuperheater to compensate for the effect on the steam temperature of certain factors amongst which is the presence of ash on the superheater elements or boiler tubes. Conveniently the pipe 7 conveying steam from the superheater 6 to the desuperheater 1 of the apparatus according to Fig. 1 is divided or bifurcated at 13, 14 for an appropriate distance, one leg 13 of the bifurcated section constituting a fixed resistance, and there being provided in the other leg 14 a variable resistance 15. The fixed resistance 13 would be of such a value as to obtain a predetermined pressure drop with the variable resistance 15 at its maximum opening, and thereby determine the load at which under normal conditions the desuperheater 1 will commence to operate. The variable resistance 15 may be a valve of any appropriate type adapted to be adjusted from time to time as necessary, either by the boilerhouse engineer, or automatically by thermostatically controlled means, the thermostat being located at the outlet from the desuperheater. Opening or closing the variable resistance 15 will reduce or increase the pressure drop between the steam space of the boiler and the desuperheater, and thus determine the water level in the desuperheater. Preferably the apparatus would be such that with all conditions normal, at a predetermined boiler load, the desuperheater would be free from water or would

contain a very small quantity of water. On an increase in steam temperature occurring, due to a rise in the load, the water level in the desuperheater will rise, on account of the increase in the pressure drop as between the steam space of the boiler and the desuperheater. Should deposits on the superheater or boiler tubes, fall in feed water temperature, or other conditions, cause the temperature of the steam delivered by the superheater to vary, such variation will be compensated for by variation in the pressure drop effected by adjusting the variable resistance 15, either by hand or automatically, as already referred to.

15 It is also in accordance with the present invention to supply water to the desuperheater 1 from the feed water line 16 instead of from a boiler drum as in the embodiment of the invention shown in Fig. 1. By taking the water supply for the desuperheater from the feed line greater purity of the water in the desuperheater is obtained and the necessity for blowing down the desuperheater water is reduced to a minimum. The deposit of impurities on the water-touched surfaces of the tubes 4 of the desuperheater apparatus is minimized by the use of the pure, or relatively pure, feed water. In carrying this part of the present invention into practice the pipe 2 connected to the bottom of the water space of the desuperheater is a branch pipe taken from the boiler feed line 16 between the feed valve 17 and the boiler drum 3 and thus the water space of the desuperheater is in constantly open communication with the boiler drum. As in the apparatus according to Fig. 1 a resistance or choke 18 of predetermined fixed value is inserted in the pipe 2 feeding water to the desuperheater in order to reduce the extent of variation of water level in the desuperheater 40 due to variation in the pressure drop across the superheater and thus permit the height of the desuperheater apparatus to be reduced. Conveniently the water feed pipe 2 to the desuperheater instead of being connected to the water space of the desuperheater through the side wall of the latter, may be connected to a passage through the bottom wall 18 of the water space of the desuperheater constituting the tube plate thereof, which wall or plate 18 would have a 45 thickness appropriate for the purpose.

50 In order to compensate for the variation in superheat which accompanies a variation in rate of water feeding, a resistance or choke 19 is provided in the portion 20 of the feed pipe 16 between the branch pipe 2 to the desuperheater and the boiler drum 3. The value of the resistance 19 will be such that the increase in the drop in pressure of the water in passing through such resistance will cause a rise of the water level in the desuperheater 1 sufficient to compensate for the increase in superheat produced by the increase in the rate of water feeding. A reduction in the rate of water feeding likewise produces a fall of water level.

65 By supplying the desuperheater with water from the feed water line the effect on superheat of variation in feed water temperature is wholly or partly compensated for, since a fall in feed temperature which will cause the superheat to increase also increases the rate of heat transfer in the desuperheater.

70 It is within the ambit of the invention to include in the apparatus certain by-passes equipped with controlling valves which may be actuated automatically or manually as desired.

75 A connection 21, equipped with a valve 22, bypassing the superheater 6 may be provided between the pipe 23 leading to the inlet header 24 of the superheater 6 and the pipe 7 conveying steam to the desuperheater 1, in which case the bifurcated section 13, 14 and valve 15 may be omitted, the pipe 7 remaining as in Fig. 1 and as shown in dotted lines in Fig. 2. If for any reason a low superheat temperature persists an appropriate quantity of saturated or low temperature steam may be taken from the inlet header and mixed with the steam entering the desuperheater. Thus a reduced pressure drop between the boiler drum and the desuperheater is effected, the water level falls, and a reduction in the amount of desuperheating results.

10 A pipe 25 by-passing the desuperheater 1 may be provided in order that, if desired, an appropriate quantity of steam may pass to the boilerhouse range or the secondary superheater 20 without passing through the desuperheater, the said quantity of steam being mixed with the desuperheated steam.

15 The provision of this by-pass 25 enables the diameter of the desuperheater 1 to be reduced 25 and by appropriately increasing the length of the tubes 4 the required amount of desuperheating can be effected without resorting to excessive steam velocity through the desuperheater. This by-pass 25 may be permanently open, or may 30 have a valve 26 which may be thermostatically controlled or manually operable, or it may have both a thermostatically controlled valve and a manually operable valve.

25 By using water from the feed line as the cooling fluid in the desuperheater 1 the latter may be reduced in size to a certain extent as compared with the apparatus shown in Fig. 1 as the feed water is at a lower temperature than the water in the boiler drum. The feed water, as already indicated, is more nearly pure than is the boiler water, and less frequent blowing down of the water in the desuperheater will be necessary, but if desired, in order to avoid the necessity of blowing down, means may be provided 40 whereby water from the feed line will flow through the desuperheater into the boiler so that a stagnant body of water does not obtain therein, but the water is constantly being changed. To effect this the apparatus shown in 45 Fig. 2 may be modified as shown in Fig. 3, there being provided according to this embodiment of the invention an ejector-like apparatus 27 in the section 20 of the feed pipe 16 between the boiler drum 3 and the pipe 2 leading to the desuperheater 1; the ejector-like apparatus 27 may comprise a Venturi tube 28, and the Venturi tube make take the place of the resistance or choke 19 in the said pipe 20 or the two may be used together as shown. To the restricted portion or 50 throat of the Venturi tube 28 there is connected a pipe 29 which communicates with the water space of the desuperheater 1 at 30 close to the bottom thereof, and at one or more places 31 in its height. The throat of the Venturi tube 28 55 also is connected with the interior of the desuperheater casing at a point 32 above the intended highest water level of the desuperheater. If desired, instead of a common connection from the Venturi tube to the water and steam spaces 60 of the desuperheater the steam space may be connected to the Venturi tube by an independent duct or pipe 33 as shown. The connection at 32 has for its object to prevent water flowing over into the open ends of the tubes 4 of the desuper- 65

70

75

heater, the said connection being made at a point below the upper ends of said tubes. As water is fed to the boiler by the pipe 16 an ejector action takes place at the Venturi tube 28 which draws 5 water from the water space of the desuperheater through pipe 29, fresh feed water flowing in through pipe 2 to maintain the water level. By this means concentration of solids in the water in the desuperheater is avoided.

10 It is to be understood that, although some constructional details are shown or have been referred to herein, the invention is not restricted to such constructional details. Further it is to be understood that the desuperheater controlled in 15 the manner herein described may be disposed between the superheater and the boilerhouse range to moderate as may be necessary the temperature of the steam flowing from the superheater before it is delivered to the range, or it 20 may be interposed between the primary and final sections of the steam superheater so as to regulate the temperature of steam fed to the final section of the superheater, and thus maintain constant, or substantially constant, the temperature of steam delivered by such final section of 25 the superheater.

What I claim is:

1. In apparatus of the class described, the combination of a boiler having a water and a steam space, a superheater, a desuperheater extending above the water space of the boiler and comprising a shell, a tube sheet at its lower end and tubes fixed in the tube sheet and extending to a point adjacent to the upper end of the shell, 30 connections from the boiler to the superheater, from the superheater to the upper end of the desuperheater and from the lower end of the desuperheater to the point of use of the steam, and a connection from the water space of the boiler to the shell at a point adjacent to but 35 above the tube sheet, the last named connection having a choke opening in it, the combination further including a boiler feed line opening into said last named connection at a point between the choke and the boiler, and a further choke between said point and the boiler.

2. In apparatus of the class described, the

combination of a boiler having a water and a steam space, a superheater, a desuperheater comprising a vertically placed cylindrical shell with a tube sheet at its lower end and tubes fixed in the tube sheet and extending to a point 5 adjacent to the upper end of the shell, the tube sheet being above the water level of the boiler, connections from the boiler to the superheater, from the superheater to the upper end of the desuperheater, and from the lower end of the 10 desuperheater to the point of use of the steam, a feed water supply to the boiler with a branch to the desuperheater, a choke opening in each branch, an ejector in the branch leading to the boiler with the feed water on its way to the boiler 15 acting as ejecting fluid, and connections from the ejector to different levels of the water and steam spaces of the desuperheater, whereby feed water on its way to the boiler draws water from the water space of the desuperheater and delivers 20 it to the boiler.

3. Apparatus in accordance with claim 2, the connection from the ejector to the steam space of the desuperheater opening into the latter at a point below the upper ends of the tubes but above 25 the intended highest water level in the desuperheater.

4. In apparatus of the class described, the combination with a boiler having a water space and a steam space, and a superheater, of a desuperheater disposed above the water space of the boiler and comprising a shell, a tube sheet at its lower end, and tubes fixed in the tube sheet and extending to a point adjacent to the upper end of the shell; a connection from the boiler 30 to the superheater; a connection from the water space of the boiler to the shell at a point adjacent to but above the tube sheet for supplying water to the desuperheater; a connection from the superheater to the upper end of the desuperheater subjecting the water therein to the pressure of steam entering the latter from the superheater; and a connection from the lower end of the desuperheater to the point of use of the steam.

JOHN EDWIN WOOD.
